UNITED STATES PATENT OFFICE.

JOHN W. MYERS AND CLARENCE A. MYERS, OF QUINCY, ILLINOIS.

DESIGN FOR A PUNCH-BODY.

SPECIFICATION forming part of Design No. 33,857, dated January 8, 1901.

Application filed August 16, 1899. Serial No. 727,448. Term of patent 14 years.

To all whom it may concern:

Be it known that we, JOHN W. MYERS and CLARENCE A. MYERS, of Quincy, in the county of Adams and State of Illinois, have 5 invented and produced a new and original Design for a Punch-Body, of which the following is a specification, reference being had to the accompanying drawing, forming part thereof.

As shown in the drawing, the leading or 10 material feature of our design consists of the compound-curved handle portion A, which curves upwardly and downwardly at the points B and C, respectively, into a relatively flat head portion D, having an opening there- 15 in, as shown at H, the lower portion of the

part D being continued forward to form the projection E. The portion D has formed on the front face the cylindrical-shaped projection F, whose lower portion is pointed or cone-shaped, as shown at G, and is directly over 20 the projection E.

We claim—

The design for a punch-body herein shown and described.

JOHN W. MYERS.
CLARENCE A. MYERS.
